US00D622959S

(12) **United States Design Patent**
Zalewski et al.

(10) **Patent No.:** **US D622,959 S**
(45) **Date of Patent:** **** Sep. 7, 2010**

(54) **STORAGE UNIT**

(75) Inventors: **Kevin Zalewski**, Rochester Hills, MI (US); **David Foster**, Farmington Hills, MI (US); **Dirk Ahlgrim**, Cambridge, MA (US); **Jared Judson**, Medford, MA (US); **Monica Kuznik**, Padova (IT); **Samuel Palmer**, Arlington, MA (US); **Gretchen Wustrack**, San Francisco, CA (US)

(73) Assignee: **Target Brands, Inc.**, Minneapolis, MN (US)

(**) Term: **14 Years**

(21) Appl. No.: **29/333,915**

(22) Filed: **Mar. 17, 2009**

(51) LOC (9) Cl. **03-01**

(52) U.S. Cl. **D3/273**

(58) Field of Classification Search **D3/272, D3/273, 283, 302, 304-315, 319, 320, 335, D3/336, 396; D6/397, 449, 475, 476, 510; D9/414, 418, 499, 432, 433; D19/90; 206/515, 206/527, 784, 815; 220/9.1, 9.3, 62, 475, 220/639, 641, 646, 647, 890, 913; 229/100, 229/117.01, 117.07, 120, 120.1**

See application file for complete search history.

CLAIM

The ornamental design for a storage unit, as shown and described.

DESCRIPTION

The present application is related to pending U.S. Utility patent application Ser. No. 11/851,165, entitled “Storage and Organization System and Components Thereof,” filed Sep. 6, 2007; pending U.S. Design application Ser. No. 29/284,375, entitled “Storage Bin,” filed Sep. 6, 2007; pending U.S. Design application Ser. No. 29/284,379, entitled “Lid Portion,” filed Sep. 6, 2007; pending U.S. Design application Ser. No. 29/329,629, entitled “Storage Bin,” filed Dec. 18, 2008; pending U.S. Design application Ser. No. 29/333,916, entitled “Drawer and Door,” filed Mar. 17, 2009; pending U.S. Design application Ser. No. 29/333,917, entitled “Supporting Base,” filed Mar. 17, 2009; and pending U.S. Design application Ser. No. 29/333,918, entitled “Tray,” filed Mar. 17, 2009; all of which are incorporated herein by reference.

FIG. 1 is a perspective view of a storage unit, according to the invention;

FIG. 2 is a front view thereof;

FIG. 3 is a back view thereof;

FIG. 4 is a top view thereof;

FIG. 5 is a bottom view thereof;

FIG. 6 is a right view thereof; and,

FIG. 7 is a left side view thereof.

The broken lines in the drawings represent unclaimed environmental matter.
